UNITED STATES PATENT OFFICE

MAXWELL M. UPSON, OF ENGLEWOOD, NEW JERSEY, AND HERMAN R. SMITH, OF DOUGLASTON, NEW YORK, ASSIGNEES TO RAYMOND CONCRETE PILE COMPANY, OF NEW YORK, N. Y., A CORPORATION OF NEW JERSEY

REINFORCED PILE SHELLS

Application filed May 2, 1929. Serial No. 359,789.

This invention pertains to shells for concrete piles, with special reference to shells adapted for severe conditions, under which the ordinary shells are liable to be cut or punctured during the driving operation.

It is sometimes necessary to penetrate a stratum of gravel or hard cutting material in order to reach a substantial bottom. While passing through such a stratum the pile shell 10 is liable to be punctured, thus permitting water and sand to enter the shell, frequently to such a degree as to render it impossible to clean out the water and sand and therefore necessitating the driving of another pile and 15 adding greatly to the expense of the job.

For illustrative purposes our invention is shown in connection with a well known type of shell which is spirally corrugated and has heavy steel wire wound in the corrugations. 20 The spiral wire and corrugations form a very strong and rigid shell which under most conditions will withstand the compression of the earth and maintain a hole after the core or collapsible mandrel is withdrawn. As usually 25 made, it is necessary to corrugate the shell rather deeply in order to hold the wire firmly in position. This renders the metal of the corrugations particularly vulnerable to abuse during the driving operation, and punctures 30 are very apt to occur at the corrugations.

This invention contemplates the use of a double metallic shell with a non-metallic waterproof material between the shells, the material being of such nature as to strengthen 35 and stiffen the structure and better enable it to resist puncture. One suitable material for such a filling is concrete, another is asphalt, but other similar substances may be used with satisfactory results.

40 If wire reinforcements are used in the shell as above described, the filling helps to hold the wire in position and the corrugations therefore do not need to be as deep as in ordinary practice, or may be entirely dispensed with, and the wires may even be in the form of rings, instead of in a continuous spiral.

45 Shallow corrugations more easily push aside the soil and do not afford ready opportunity for the cutting material in the soil to

engage and puncture the under sides of the corrugations. Furthermore, the filling material being waterproof will prevent leakage into the shell even if the metal shell be cut or punctured.

55 Further and other objects and advantages will appear from the specification and claims, and from the accompanying drawings which show by way of illustration what is now considered the preferred embodiment of the invention.

60 Fig. 1 is a view in cross-section of a lower pile shell section made according to the present invention, surmounted by other shell sections of usual construction.

65 Fig. 2 is an enlarged view, partly broken away, of a shell section showing the present invention.

Fig. 3 is a section on the line 3—3 of Fig. 2.

70 The tapered outer steel shell 20 is corrugated spirally as at 22, and the reinforcing wire 24 is wound in the shallow corrugations. Within the wires is a plain steel shell 26, the space between the inner and outer shells, unoccupied by the wires, being filled with the 75 non-metallic filler 28. The larger end of each shell section is left unlined and uncorrugated, in order better to accommodate the small end of the next adjoining shell section, each complete shell for a pile being usually made up 80 of a number of sections. As is well known in the art, the shell is mounted on a core, driven to firm bottom while on the core, and the core then removed and the shell filled with concrete to form the pile.

85 In Fig. 1 the lower shell is shown of the above-described construction because it had to pass through the stratum of gravel 30 in order to reach a firm foundation. The upper shell sections, which do not need to penetrate cutting material, are of ordinary design.

90 It is to be understood that the invention is not limited to the construction and embodiment herein specified, but may be used in other ways without departure from its spirit 95 as defined by the following claims.

We claim—

1. As an article of manufacture, a permanent pile shell for driving and subsequent filling, comprising in combination, spaced inner 100

and outer shells of thin material, and a positive spacing means between said shells comprising a filler of waterproof material whereby leakage of water through said pile shell is prevented even if said outer shell and said filler are punctured.

2. As an article of manufacture, a permanent pile shell for driving and subsequent filling, comprising in combination, an outer 10 corrugated metallic shell, reinforcing wires in the corrugations, an inner shell within said wires and spaced from the outer shell thereby, and a waterproof filler between said inner and outer shells and embedding said wires.

15 3. As an article of manufacture, a permanent pile shell for driving and subsequent filling, comprising in combination, spaced outer and inner shells, corrugations in one 20 of said shells, reinforcing wires in the corrugations, and a non-metallic filler between said inner and outer shells, said filler acting to support said wires and reinforce said structure.

4. As an article of manufacture, a permanent pile shell for driving and subsequent filling, comprising in combination, spaced inner and outer metallic shells, a waterproof filler between said shells, and reinforcing wire rings embedded in said filler and engaging 30 at least one of said shells.

5. As an article of manufacture, a permanent pile shell structure for driving and subsequent filling, comprising an outer corrugated shell of thin metal, an inner shell of 35 thin metal arranged within the outer shell, reinforcing wires seated in the corrugations and projecting inwardly to space the inner shell a substantial distance from the outer shell and a non-metallic waterproof filling 40 between said shells in which said wires are embedded.

In testimony whereof we hereto affix our signatures.

MAXWELL M. UPSON.
